UNITED STATES PATENT OFFICE.

GEORGE V. KONDOLF, OF ROCHESTER, NEW YORK.

SLAB OR BRICK FOR DRIVEWAYS.

1,339,356.

Specification of Letters Patent.

Patented May 4, 1920.

Application filed October 9, 1919. Serial No. 329,562.

To all whom it may concern:

Be it known that I, GEORGE V. KONDOLF, a citizen of the United States, residing at Rochester, in the county of Monroe and 5 State of New York, have invented certain new and useful Improvements in Slabs or Bricks for Driveways, of which the following is a specification.

The object of this invention is to provide 10 a new and improved form of slab or brick which is so constructed that a number of them can be tied together in series and anchored on the surface of the ground to form a continuous road bed for a driveway 15 for automobiles or other vehicles.

Another object of this invention is to provide a temporary tie rod for each series of 20 slabs or bricks, which tie rod is adapted to be laid over the course of the driveway preliminary to the laying of the slabs or bricks.

Another object of this invention is to provide suitable spacing bars for the tie rods and slabs or bricks, to properly space a pair 25 of series of slabs or bricks from each other to form a double track driveway.

Another object of this invention is to provide anchors on the bottom of each of the slabs or bricks with which the slabs or bricks are individually anchored to the tie rod and 30 to the surface of the ground to prevent any lateral shifting of any one of the slabs or bricks.

These and other objects of this invention will be fully illustrated in the drawings, described in the specification and pointed out 35 in the claims at the end thereof.

In the accompanying drawing:

Figure 1 is a sectional perspective view 40 of the driveway laid with the slabs or bricks.

Fig. 2 is a bottom plan view of a series 45 of slabs or bricks showing the tie rod that holds them together and in line with each other.

Fig. 3 is a perspective view of the slab 50 or brick provided with a modified form of anchor.

Fig. 4 is a perspective view of the slab or 55 brick provided with another modified form of anchor.

Fig. 5 is a perspective view of a portion 60 of a driveway made up of the slabs or bricks and tied together with a pair of tie rods which in turn are spaced apart and tied together by a spacing rod so as to line up the 65 rails made up of each series of slabs or bricks

parallel to each other, the driveway being viewed from below.

In the several figures of the drawing like reference numerals indicate like parts.

Many of the driveways laid for private 60 garages are formed by a pair of parallel rails which are spaced apart according to the width of the wheel base of the automobile. It is for such a drive way that the slabs forming the subject matter of this invention are especially adapted although any other common form of driveway may be 65 laid with the aid of these slabs.

Each of the slabs or bricks 1 is made up 70 of concrete or other suitable material that can be cast or pressed into the desired shape with suitable reinforcements or binding material embedded therein. The top surface of each of the slabs 1 may either be made flat as shown in Fig. 1 or it may be made 75 slightly crowned as shown in Figs. 3 and 4. Suitably embedded and projecting out from the bottom of each of the slabs 1 are the spikes or anchors 2 and 3. These anchors are properly spaced apart and are preferably 80 located in the middle of the bottom face of the slab. The anchors 2 and 3 are held in place therein by casting them into the material when the slab is made. If necessary, a tie rod 4 may be used to hold the 85 anchors in their proper places while the material from which the slab is formed is hardening around them. The tie rod 4 may be supplemented by other tie rods which, when provided, form reinforcing bars for 90 the slabs.

The slabs 1 are tied together and lined up with one another by means of the tie rod 5 which is preferably made up of a flat strip of metal. This tie rod is provided with 95 a series of holes 6 and 7 which are equally spaced apart at intervals corresponding to the distance the anchors 2 and 3 are spaced apart on the bottom of each of the slabs 1.

The driveway made up of these slabs, is 100 laid by first placing the tie rods 5 on the surface of the ground at the point and in the direction the rails of the driveway are to be laid. For the purpose of spacing these tie rods the required distance from 105 each other, spacing bars 8 may be used and placed either on top or below the tie rod 6. The spacing bars 8 are provided with a pair of holes 9, 9, which holes are adapted 110 to register with one of the holes 6 and 7

in each one of the tie rods 5 used for the driveway.

After the tie rods 5 and spacing rods 8 have been laid over the course which the drive is to follow, the slabs 1 are placed 5 on top of the tie rods 5 in such a way that the anchors 2 and 3 thereof engage the holes 6 and 7 in the tie rods 5. In doing so the ends of the slabs 1 abut each other and form 10 a continuous solid rail or rails.

In order to prevent the individual slabs 1 or a continuous series of them from moving laterally and out of parallel with each other, each of the slabs may be provided 15 with an additional set of anchors 10 and 11 or 10' and 11'. These last mentioned anchors are preferably provided near the outside of the bottom of the slabs as shown in Figs. 3 and 4.

20. The anchors 10 and 11 shown in Fig. 3 are each formed of a strip of angle iron of which one side together with a portion of the other side is embedded in the slab, while the remaining portion of the side not embedded therein is left to project out at the bottom thereof. A pair of these angle irons is used for each of the slabs and, if desired, these angle irons may be tied together by means of the tie rods 12. The tie rods 12 25 in addition to spacing and holding the angle irons in place in the slab, form reinforcing rods for the material from which the slab is made.

The anchors 10' and 11' shown in Fig. 4 30 are made up and fastened to the slab 1 in the same manner as are the anchors 2 and 3 but while round spikes are shown as forming these anchors, flat stock may be used instead as shown at 14, 15, 16 and 17 at 35 the right of Fig. 2. When flat stock is used to form the anchors, the holes in the tie rod 5 must be made correspondingly elongated so that the anchors 14, 15, 16 and 17 40 can engage therein. The anchors 10 and 11 shown in Fig. 3 do not run the full length 45 of the slab or brick, but stop short of the anchors 2 and 3 in the center of the slab. This is necessary in order that the spacing bars 8 can engage with the anchors 2 and 3.

50. In laying this driveway, the slabs are placed on the surface of the ground rigidly tied together and properly spaced apart and each individual slab is anchored to the ground as above pointed out. This makes 55 the driveway, when completed, project

above the ground a distance equal to the thickness of the slabs. As soon, however, as the driveway is being used the weight of the automobile or the other vehicles traveling over the driveway will gradually force the slabs into the ground so as to make the top surface flush with the surrounding ground. This eliminates the laying of a foundation as the ground thus compressed forms an ideal foundation itself. 60

65. I claim:

1. A driveway for automobiles, etc., comprising a series of slabs or bricks, each of said slabs or bricks being provided with anchors projecting out from the bottom thereof, a tie rod having holes therein placed below said slabs or bricks to hold a series of said slabs or bricks together and in line with one another, said anchors being adapted to pass through the holes in said tie rod and project into the ground. 70

2. In a slab for building driveways the combination of a flat body, a pair of anchors projecting out from the bottom thereof parallel with the sides of said body, and means to connect successive slabs to one another. 75

3. In a slab for building driveways, the combination of a flat body, an anchor projecting out from the bottom near each side thereof, said slabs being adapted to be placed on the surface of the ground with said anchors projecting into it to prevent displacement thereof. 80

4. A driveway comprising a row of flat slabs having their ends abutting one another, downwardly projecting anchors, one near each side of each of said slabs to prevent their displacement sidewise and keep said slabs in line with one another, other anchors near the center of said slab to prevent their displacement endwise and means to connect the anchors of consecutive slabs with one another. 85

5. A driveway comprising a pair of rows of flat slabs having their ends abutting one another, downwardly projecting anchors in the bottom of said slabs, tie rods to connect the anchors of the consecutive slabs in each of the rows of slabs comprising said driveway and tie rods to connect the anchors of oppositely placed slabs in the two rows of said driveway. 90

100. In testimony whereof I affix my signature.
GEORGE V. KONDOLF.
